WRAPPING MACHINE SEALING AND
DETECTOR MECHANISM

Michael J. Milmoe, Glen Ellyn, and Clarence J. Malhiot, Oak Park, Ill., assignors to F. B. Redington Co., Chicago, Ill., a corporation of Illinois

Application February 15, 1937, Serial No. 125,804

17 Claims. (Cl. 91—45)

This invention relates to wrapping machines in general and particularly to a machine for wrapping and sealing or closing packages.

The primary object of the present invention is to provide new and improved means for sealing a package and effecting a tight seal by the use of an ejector or blowing mechanism which will blow a predetermined amount of wax or other adhesive into an open end of a wrapper to be sealed, in connection with the provision of means for preventing the operation of the ejector means when a package is not in position to receive the wax or other adhesive.

Other objects of the invention are the provision of an adhesive applying mechanism which has a new and novel adhesive carrying element or pot, which is provided with new and improved means for closing and opening the adhesive applying passage, which has detector means for preventing the operation of the applying means when a package is not in proper adhesive receiving position, which is provided with means for measuring and carrying a predetermined amount of wax or adhesive to position, and which is provided with means for causing the amount of adhesive or wax carried by the adhesive carrying means to be discharged at a predetermined timed interval with respect to certain other operations of the machine.

Still another object of the invention is the provision of a new and novel arrangement of parts and elements constructed and arranged to operate in a predetermined proper sequence to effect a proper and correlated operation of a sealing mechanism.

A still further object of the invention is the provision of a new, novel and simple sealing and detector mechanism which is adapted to be readily applied to existing machines or which is capable of being readily incorporated in a newly constructed device, and which is composed of few and simple parts, relatively few of which are operated and which are not likely to get out of order.

Numerous other objects and advantages will be apparent throughout the progress of the following specification.

The accompanying drawings illustrate a selected embodiment of the invention and the views therein are as follows:

Fig. 1 is a detail elevational view of a wrapping and sealing machine and embodying the invention.

Fig. 2 is a detail plan view of the improved wrapping and sealing means shown in Fig. 1.

Fig. 3 is a detail sectional view showing the position of some of the elements for sealing a wrapper, the operating rod being shown as nearing the limit of its upward travel.

Fig. 4 is a detail elevational view showing the position of the detector mechanism when a package is in proper position.

Fig. 5 is a similar view showing the detector mechanism when no package is arranged in position.

Fig. 6 is a detail sectional view of a package showing the position of the package for receiving the sealing or waxing treatment.

Fig. 7 is a detail sectional view on the line 7—7 of Fig. 2, showing the parts at the limit of their upward movement and in operating position.

Fig. 8 is a view similar to Fig. 7, but shows one rod at the limit of its upward travel and the other rod in its lowermost position and unaffected by the operation of the operating rod.

Fig. 9 is a detail view of one form of package showing the outer wrapper in sealed position.

Fig. 10 is another form of carton to which the method is readily adaptable.

The invention is adapted to be applied to existing machines, or it may be incorporated in a newly constructed machine. In the present embodiment shown in the figures herein the invention is applied to a particular type of wrapping machine for wrapping stacked circular articles. However, the drawings disclose only one embodiment of the invention for illustrative purposes only.

The machine to which the invention is applied comprises a suitable frame or supporting structure in which a driven shaft 9 is suitably journaled. The shaft 9 has fixed thereto for rotation therewith a conveyor 10, which in the present instance is circular in the form of a wheel, there being a plurality of flexible spaced carriers 11 each including a supporting portion 12 and a spring pressed article supporting finger 13, Fig. 1. Packages 14 are carried about the periphery of the conveyor and held by the carriers 11.

The packages 14, Fig. 6, each comprise an inner wrapper 15 wrapped about a plurality of stacked circular articles 16. An outer wrapper 17 is wrapped about the wrapper 15 and is tubular in shape. The end of the tubular wrapper 17 extends a predetermined distance beyond the end 18 of the inner folded wrapper 15. The outer wrapper, therefore, has an extension 19 which is adapted to be again folded about the once wrapped article. The method of arranging

the wrapper and sealing the ends may be as disclosed in Patent No. 2,019,191, issued October 29, 1935, and assigned to the present assignee. An opening tape, as set forth in said patent, may be included.

A wax pot or other adhesive carrying receptacle 20 is arranged in juxtaposition with respect to the article carrying mechanism to permit the open end of a wrapper about an article to be sprayed with a predetermined amount of wax or other adhesive so that when the outer wrapper is folded down in position a tight seal is effected.

The receptacle 20 is adapted to contain a predetermined quantity of wax or other adhesive 21 and where wax is used as the sealing agent, heating elements 22 may be provided for melting the wax and maintaining the same at a predetermined operating temperature. The receptacle 20 is provided with a lug or boss portion 23 to provide a bearing for the vertically movable valves or rods 24 and 25, Figs. 3, 7 and 8.

The bearing 23 is provided with a transverse bore or passage 26 to which an air pipe or line 27, Fig. 7, leading to a source of air pressure (not shown), is connected to provide a passage from the air pressure means to a nozzle 28. The bore 26 transverses the bores 29 and 30 provided in the bearing 23 for the vertical rods or valves 24 and 25 respectively. One part of the bearing or boss 23 extends from the top of the receptacle 20 to the bottom, and it is through this solid part that the bore 26 is formed for the reception of the rod 24. The other part of the bearing or boss 23 extends only a part way down, as clearly shown in Figs. 3, 7 and 8, to permit the lower end of the rod 25 to be immersed in the wax 21, Fig. 8. The rod 24 is slidably movable in the bore 29 and extends completely through the bearing 23 throughout its entire vertical length 40 and above and below the top and bottom of the receptacle 20.

An operating head 31 is connected to the lower end of the rod 24 and is operated by operating mechanism 32 to cause vertical movement of the rod 24. This operating mechanism 32 is operatively but resiliently connected and correlated with the means which operates the package carrying member or wheel 10 so that operation of the rod 24 is synchronized with the operation of the drive shaft 9 of the article carrying wheel 10. This operating mechanism 32 is provided with a resilient feature, as will later be described, so that jars and strains are taken off the parts should the rod 24 be stuck for some reason or other, such as the freezing or caking of the wax.

A spring 31a encircles the lower end of the shaft or rod 24 and is arranged between the bottom of the receptacle 20 and the upper surface of the member 31. The purpose of this spring is to lower the rod 24 after it has been raised by the operating means 32.

A lug 33 is fixed to the shaft or rod 24 and is provided with a three-sided opening 34 therein to receive the upper squared portion 35 of the rod 25. The open side of the lug 33 is adapted to have a plate 36 attached thereto to close the open side of the opening 34 so that the rod 25 will be completely surrounded. The plate 36 is a friction plate and is held in position by the fastening members 37 and their co-operating springs 38. A pressure is, therefore, exerted against the rod 25 providing a friction contact between the lug 33 and the shaft 25. Therefore,

when the rod 24 is reciprocated vertically, the frictional contact between the lug 33 and the rod 25 is such as to cause the lug 33 to reciprocate the rod 25.

The rods 24 and 25 are each provided with transverse bores 39 and 40, respectively, which are adapted to be brought into alignment with the passage 26 in the bearing member 23. When the bores 39 and 40 are in alignment with the passage 26 air pressure is free to pass through the ejector nozzle 28. The nozzle 28 is, of course, positioned relative to the open end of the cylindrical outer wrapper 17 to spray the closed end 18 of the inner wrapper with a predetermined quantity of wax, Fig. 6. The rod 25 carries a predetermined quantity of wax in the bore 40 and, therefore, when the bores 39 and 40 of the rods 24 and 25, respectively, are in alignment with the passage 26 in the bearing 23 the wax in the bore 40 of the rod 25 is blown out of the nozzle 28 against the end of the article package. Means (not shown) are then operated to fold over the end of the outer wrapper 17 in any desired manner, such as disclosed in the aforesaid Patent No. 2,019,191.

During operation of the driving means the rod 24 is moved upwardly against the tension of the spring 31a. Upward movement of the rod 24 will normally cause upward movement of the rod 25 because the lug 33 is fixed to the rod 24 and has frictional engagement with the rod 25, the friction being sufficient to raise the rod 25 under normal operating conditions. When the rod 24 has reached the limit of its upward travel, the passage 39 in the rod 24 will be in alignment with the passage 26 in the bearing 23. The rod 25, which is being raised by the rod 24, will be limited in its upward movement by a stop 41 whereby the passage 40 in the rod 25 will be in alignment with the passage 26. As shown in Fig. 7, the air pressure coming through the line 27 will then blow out any wax which is in the passage 40 in the rod 25 and force this wax out of the nozzle 28 against the folded end of the inner wrapper 17.

After the waxing operation has been completed the operating mechanism 32 will be withdrawn from the operating boss 31 and the spring 31a will return the parts to normal inoperative position because the movement of the rods in their bores will bring the passages 39 and 40 out of alignment with the passage 26 and, therefore, the air supply from the line 27 is shut off. When the rod 24 moves downwardly the rod 25 will also be caused to move downwardly because of the frictional engagement of the rod 25 with the lug 33. The downward movement of the rod 25 is limited because of the engagement of the bottom of the rod 25 with the bottom of the receptacle 20. Excess or over-movement of the rod 25 in either direction will not be transmitted to the rod 24 because of the sliding frictional engagement. Therefore, when the rod 25 reaches the stop 41 the rod 25 will cease to move even though the rod 24 continues upwardly (compare Figs. 3 and 7). Likewise, downward movement of the rod 25 will cease when the bottom of the rod 25 engages the bottom of the receptacle, as shown in Fig. 8, even though the rod 24 should continue downwardly. However, the passage 39 in the rod 24 is so positioned with respect to the mechanism that operates the rod that at the limit of the upward movement of the rod 24 the passage will be in the position shown in Fig. 7. Therefore, during reciprocation of the rod 24

the rod 25 will also be reciprocated and positioned by stop 41 and the passages 39 and 40 will be brought into alignment to permit the air pressure to blow the wax in the passage 40 out of the nozzle 28.

During each reciprocation of the rod 25 the lower end of the rod is immersed in the liquid wax 21 and a predetermined amount of wax is deposited in the passage 40. The wax can not escape from the passage 40 as the normal wax line is above the lower end 42 of the bearing 23 and, therefore, is confined by the material of the boss which surrounds the bore 30.

Of course, it is desirable and really necessary that no wax be sprayed when no wrapped article 14 is in position to receive the wax. Therefore, detector means are provided to prevent the passage 40 from coming into alignment with the passage 26 when no article is in position to receive the wax treatment.

This detector mechanism comprises a feeler 43, Figs. 2, 4 and 5, which is carried by a feeler arm 44. This feeler arm 44 is rigidly mounted on a transverse shaft 45 which is journaled in a bracket 46 mounted on top of the wheel guard 47. The feeler 43 is positioned in the path of a package 14 and thus when a package 14 engages the feeler 43 the shaft 45 will be given a part rotation. The rod 45 has fixed thereto a downwardly extending arm 48 having an operating lug 49 at its lower end. Therefore, any movement given the shaft 45 by the operation of the feeler 43 is transmitted to the arm 48 and consequently the lug 49. The lug 49 on the arm 48 is adapted to engage a recess or notch 50 formed in the square portion 35 of the rod 25, and when so engaged will lock the rod 25 from vertical movement. Therefore, when a package 14 is in position, as shown in Fig. 4, it will engage the feeler 43 and cause the feeler 43 and its connecting arm 44 to give the shaft 45 a slight rotation. This rotation of the shaft 45 swings the arm 48 and consequently the lug 49 in a clockwise direction, Fig. 4, and moves the lug 49 out of the slot or notch 50 to the position shown in Fig. 4, thereby allowing vertical movement of the rod 25 and permitting the waxing of the package. If, however, there is no article 14 in position, the parts will be in the position shown in Fig. 5 wherein the lug 49 is engaged in the notch 50, thereby preventing vertical movement of the rod 25. The vertical movement of the rod 24, however, is unhampered and the lug 33 will merely slide on the rod 25 during the vertical reciprocation of the rod 24 when the lug 49 is in engagement with the notch 50, as shown in Fig. 5. When the machine continues to operate and the next succeeding package is fed to the position shown in Fig. 4, the feeler element will again cause the lug 49 to be removed from its recess and therefore permit normal operation of the rod 25 and the subsequent waxing of the package.

Because of the possibility of the operating rod 24 sticking because of certain conditions, such as the cooling or freezing of the wax in the receptacle 20, the means for operating the rod 24 are resilient whereby the driving parts can operate in their normal manner without breaking or damaging other parts because of the sticking of the rod 24.

This flexible operating mechanism 32 may comprise an arm or bracket 51, Figs. 1 and 4, which has a boss 52 through which a vertical rod or shaft 53 extends. The rod or arm 51 has

an operating head 54 which has face to face contact with the member 31. The journal or boss 52 on the member 51 is fixed to the shaft 53 in any suitable manner such as by a pin 55 whereby the rod 53 is rigidly connected to the arm 51. Upper and lower bearings 56 and 57, respectively, are fastened to part of the machine frame and provide a sliding bearing for the shaft 53. The arm 51 has an extension or tail piece 58 through which a rod or shaft 59 passes. Nuts or stops 60 are fastened to the shaft or rod 59 and a spring 61 is interposed between the lower nut 60 and the under side of the tail piece 58. The rod or member 59 is reciprocated in any well known manner such as by a cam or crank (not shown) but, of course, is synchronized with the operation of the rest of the machine to cause vertical reciprocal movement in timed relationship with the movement of the feed wheel 10 whereby intermittent synchronized movement of the shaft 24 is caused.

The spring 61 has sufficient strength so that normally it holds the tail piece 58 in engagement with the collar 60, as shown in Fig. 4, the shaft 59 and the arm 51 moving as a unit to impart the necessary timed and controlled motion to the shaft 24. However, in the event shaft 24 should stick or otherwise become jammed, spring 61 will yield, as shown in Fig. 1, thereby permitting the operating shaft 59 to move without imparting the corresponding motion to the arm 51. Spring 31a normally holds members 31 and 54 in contact, thereby returning or lowering the shaft 24 as the arm 51 is lowered.

The invention is particularly adaptable for a package as disclosed in the aforesaid Patent No. 2,019,191 and as disclosed in Fig. 9. However, other types and forms of packages and cartons may be also employed.

In carrying out the method a predetermined quantity of wax is sprayed in mist form within the tubular extension of the outer wrapper and against the exterior surface of the inner wrapper or carton so as to thoroughly impregnate the free ends of the outer wrapper and to provide a base portion against which the wrapper may be folded. After a predetermined quantity of wax is sprayed, the outer wrapper may be folded down and over into the position shown in Fig. 9.

The invention also contemplates spraying wax against the end of a carton or package so that when the free ends of the outer wrapper are folded down over the carton flaps as shown in Fig. 10, a tight seal is provided. It is to be understood that the invention is not limited to the specific forms disclosed as the package may include any geometrical figure or configuration.

The invention provides a sealing mechanism for making a tight seal on a package. A passage leading to a source of air pressure is opened and closed by the operation of the rods 24 and 25 and the amount of wax to be blown through the nozzle 28 when all the parts are in operating position is determined by the size of the orifice or passage 40 at the end of the rod 25. After the wax or other adhesive is blown or sprayed into the open cylindrical end of the outer wrapper, the wrapper is creased and folded against the end of the package whereby a tight seal is effected. By delivering a predetermined quantity of wax to a predetermined position and then causing this wax to be ejected against the end of the package or article in a spray or mist form, the entire wrapper surface to be folded is impregnated with the wax or other adhesive and then finally, when the carton flaps or outer

wrapper folds are folded down in position, the wrapper will be fixed to the package and a tight seal will be effected. The detector mechanism is simple in construction and positively controls the operation of the wax spraying means depending upon whether or not a package is in position to be operated upon.

The device is capable of being applied to existing machines as well as being incorporated in new machines, and the means for operating the rod 24 is relatively flexible so as to prevent breakage or damage of certain of the parts during sticking or jamming of some of the other parts.

The claims herein are directed to the apparatus disclosed, claims to the method of wrapping and sealing the packages as herein set forth being presented in a divisional application.

Changes may be made in the form, construction and arrangement of the parts without departing from the spirit of the invention or sacrificing any of its advantages and the right is hereby reserved to make all such changes as fairly fall within the scope of the following claims.

The invention is hereby claimed as follows:

1. A sealing mechanism comprising a bearing having a passage therein which leads to a source of air supply, a rod having an opening therethrough adapted to be brought into alignment with said passage, means for operating said rod in an upward direction, means for lowering said rod, a second rod, and means operated by the first named rod and frictionally engaging the second rod, to operate the second rod, said second named rod having an opening therein adapted to receive a predetermined amount of adhesive material, said second rod being controlled by the operation of the first named rod to bring the opening in the second named rod into alignment with the passage in the bearing.

2. A sealing mechanism comprising a bearing having a passage therein which leads to a source of air supply, a rod having an opening therethrough adapted to be brought into alignment with said passage, means for operating said rod in an upward direction, spring means for lowering said rod, a second rod operating in said bearing, means operated by the first named rod and frictionally engaging the second rod, to operate the second rod, said second named rod having an opening therein adapted to receive a predetermined amount of adhesive material, said second rod being controlled by the operation of the first named rod to bring the opening in the second named rod into alignment with the passage in the bearing, and means for limiting the movement of the second named rod.

3. A sealing mechanism comprising a bearing having a passage therein which leads to a source of air supply, a rod having an opening therethrough adapted to be brought into alignment with said passage, means for operating said rod in an upward direction, spring means for lowering said rod, a second rod operating in said bearing, means operated by the first named rod and frictionally engaging the second rod, to operate the second rod, said second named rod having an opening therein adapted to receive a predetermined amount of adhesive material, said second rod being controlled by the operation of the first named rod to bring the opening in the second named rod into alignment with the passage in the bearing, and detector means for preventing the operation of the second rod.

4. An apparatus for applying an adhesive to a package or article comprising a bearing having a passage therein, a rod normally closing said passage and having an opening therein, means for depositing a predetermined amount of adhesive in said opening, means to operate said rod to bring said opening into alignment with the passage in the bearing, and a source of fluid under pressure connected to said passage for expelling the adhesive from said opening and passage.

5. An apparatus for applying an adhesive to a package or article comprising a bearing having a passage therein, a valve having a passage therein adapted to be brought into alignment with the passage in the bearing, means for depositing a predetermined amount of adhesive in the valve passage, fluid means for expelling adhesive from said aligned passages, a second valve for controlling the operation of said expelling means, connections between said valves to cause said valves to operate in unison, and means for operating one of said valves.

6. An apparatus for applying an adhesive to a package or article comprising a bearing having a passage therein, a rod having a passage therethrough adapted to be brought into alignment with the passage in the bearing, means for depositing a predetermined amount of adhesive in the passage in the rod, means to operate said rod to bring the passage in the rod in alignment with the passage in the bearing and fluid pressure means for expelling adhesive from the aligned passage and upon an article.

7. In a sealing machine for packages and the like, a source of adhesive supply, an air supply source, a member having a passage therein communicating with the source of air supply, a second member having a passage therein adapted to receive adhesive from the source of supply, and means including a load releasing drive connection for moving said second member to bring the passage therein into alignment with the first named passage, locking means operable to prevent movement of said second member by said load releasing drive connection, and detector means operatively connected to said locking means for actuating said locking means when a package is not in position to receive adhesive.

8. In a sealing machine having means for transmitting an article to a predetermined position, the combination of means for applying an adhesive to the article and comprising a source of adhesive supply, an air supply source, a member having a passage therein communicating with the source of air supply, a shiftable member having a passage therein adapted to receive adhesive from the source of supply, and a reciprocal member for operating said shiftable member to bring the passage therein into alignment with the first named passage.

9. An apparatus for applying an adhesive to a package or article comprising an adhesive supplying reservoir, a bearing extending into the reservoir, said bearing having a passage therein above the level of the adhesive in said reservoir, a valve shiftably mounted in said bearing and having an opening adapted to receive adhesive from said reservoir when said valve is in one position, a rod shiftably mounted in said bearing for operating the valve from said one position to another position in which the opening therein is in alignment with the passage in the bearing and a source of fluid under pressure connected to the passage in the bearing for ex-

pelling adhesive from said opening when the same is alined with said passage.

10. An apparatus for applying an adhesive to a package or article comprising an adhesive supplying reservoir, a bearing in said reservoir, said bearing having a passage therein above the level of the adhesive in said reservoir, a source of air under pressure connected to the passage in the bearing, a rod shiftably mounted in said bearing and having an opening adapted to receive adhesive from said reservoir in one position of the rod, a valve shiftably mounted in said bearing for operating the rod from said one position to another position in which the opening therein is in alinement with the passage in the bearing, said valve normally closing said passage and having an opening therein for permitting the air under pressure to expel the adhesive contained in the opening of said rod when the opening in the valve is alined with said passage, and means for operating said valve.

11. An apparatus for applying an adhesive to a package or article comprising an adhesive supplying reservoir, a bearing in said reservoir, said bearing having a passage therein above the level of the adhesive in said reservoir, a rod shiftably mounted in said bearing and having an opening adapted to receive adhesive from said reservoir in one position of the rod, a second rod shiftably mounted in said bearing, means operated by the second rod and frictionally engaging the first rod to move said first rod from said one position to a position in which the opening in the first rod is in alinement with the bearing passage, and a source of fluid under pressure connected to the passage in the bearing for expelling adhesive through the alined passages and upon the article.

12. An apparatus for applying adhesive to a package or article comprising a bearing having a passage therein, a source of fluid under pressure connected to one end of said passage, a rod having an opening adapted to be brought into alinement with the passage in the bearing, means for depositing a predetermined amount of adhesive in the opening in said rod, a second rod shiftably mounted in said bearing and interposed between said first rod and the end of the passage to which the source of fluid under pressure is connected, said second rod having an opening therein for establishing communication between the source of fluid supply and the opening in the first rod when said last mentioned opening is in alinement with the passage in the bearing, load release means connecting the first rod to the second rod to cause said rods to operate in unison, and load release means for operating the second rod.

13. An apparatus for applying adhesive to a package or article comprising a bearing having a passage therein, a source of fluid under pressure connected to one end of said passage, a rod having an opening adapted to be brought into alinement with the passage in the bearing, means for depositing a predetermined amount of adhesive in the opening in said rod, a second rod shiftably mounted in said bearing and interposed between said first rod and the end of the passage to which the source of fluid under pressure is connected, said second rod having an

opening therein for establishing communication between the source of fluid supply and the opening in the first rod when said last mentioned opening is in alinement with the passage in the bearing, load release means connecting the first rod to the second rod to cause said rods to operate in unison, holding means operable to prevent operation of said first rod by said load release means and detector means operatively connected to said holding means for actuating said holding means when a package is not in position to receive adhesive.

14. An apparatus for supplying an adhesive to a package or article, comprising a reservoir adapted to contain a body of adhesive, nozzle means having a passage therethrough, a source of fluid under pressure connected to said passage, and means shiftable cyclically to and from the body of adhesive in the reservoir to periodically withdraw a measured amount of adhesive from said body and carry the withdrawn adhesive into the passage.

15. A sealing mechanism comprising a bearing having a passage therein which leads to a source of air supply, a rod having an opening therethrough adapted to be brought into alinement with said passage to enable the transmission of air through the passage, means for operating said rod in an upward direction, means for lowering said rod, an adhesive source of supply, a second rod having adhesive receiving means therein, said second rod being movable to move its adhesive receiving means from the adhesive source of supply into alinement with said passage to be acted on by air pressure therein, and means connecting the second rod to the first rod for operation therewith.

16. An apparatus for applying an adhesive to a package or article comprising a bearing having a passage therein, a rod having a passage therein adapted to be brought into alinement with the passage in the bearing, means for depositing a predetermined amount of adhesive in the passage in said rod, means including a second rod and friction drive connections between said rods for operating the first named rod, means for expelling the adhesive from the passages when alined and upon a package, holding means operable to prevent movement of said first rod by said friction drive, and detector means operatively connected to said holding means for actuating said holding means when a package is not in position to receive adhesive.

17. In a sealing machine for articles and the like, a source of adhesive supply, an air supply source, a member having a passage therein communicating with the source of air supply, a shiftable member having a passage therein adapted to receive adhesive from the source of supply, drive means for moving said shiftable member to bring the passage therein into alinement with the first named passage, disabling means operable to prevent shifting of said shiftable member by said drive means, and detector means operatively connected to said disabling means for actuating the disabling means when an article is not in position to receive adhesive.
